CARBURETOR

David Firth, Flint, Mich., assignor, by mesne assignments, to Borg-Warner Corporation, Chicago, Ill., a corporation of Illinois

Application February 3, 1936, Serial No. 62,179

3 Claims. (Cl. 261—34)

The invention relates generally to carburetors for internal combustion engines, and more particularly to a downdraft carburetor.

Carburetors generally may be divided into two general classes so far as the position of the throttle relatively to the fuel discharge nozzle and intake manifold is concerned, i. e., a posterior throttle carburetor wherein the throttle is positioned behind the nozzle (between the nozzle and intake manifold), so that the nozzle is on the low suction side of the throttle, and an anterior throttle carburetor wherein the throttle is in front of the nozzle (the nozzle is positioned intermediate the throttle and intake manifold), so that the nozzle or fuel discharge device is on the high suction side of the throttle. Each of the two types of carburetors has certain advantages, and each has certain disadvantages. For example, the posterior throttle carburetor is advantageous inasmuch as the metering of the fuel is accomplished on the low suction side of the throttle, thereby making it fairly easy to calibrate the fuel discharge means for part throttle mixtures. A disadvantage of the posterior throttle carburetor, however, is due to the fact that the throttle, being positioned between the fuel discharge device and the intake manifold, interferes with the flow of fuel particularly for wide-open or full-power throttle position, thus causing poor distribution of the fuel mixture to the cylinders. For this reason the anterior throttle carburetor is more advantageous so far as wide-open or full-power throttle position is concerned, since the throttle does not interfere with the flow of fuel mixture. However, because of the location of the fuel discharge device in the high suction zone of an anterior throttle carburetor, minute changes in the orifices or jets of the fuel discharge devices causes considerable change in the mixture ratio. The present invention constitutes an improvement in the form of carburetor disclosed in my copending application Serial No. 726,059, filed May 17, 1934.

It is an object of the present invention to provide a new and improved carburetor embodying certain advantages of both the posterior and the anterior throttle type carburetor, and at the same time eliminate disadvantageous features of each which were heretofore pointed out.

Another important object of the present invention is to provide a carburetor of this type embodying new and improved means for increasing the fuel supply under low vacuum conditions.

Another object is to provide a downdraft carburetor embodying a movably mounted throttle with a main fuel discharge port therein, and having improved and simplified means for varying the idling mixture supplied by the carburetor.

Another object is to provide a new and improved downdraft carburetor wherein the idling

adjustment is interrelated to and governed by the setting of the choke valve.

Another object is to provide a new and improved carburetor having a plurality of accelerating pumps connected into the main air and fuel passage of the carburetor in such a manner as to insure proper and efficient mixture of the fuel and air.

Another object is to provide a carburetor wherein a throttle member having a main fuel discharge port at one of its edges is arranged to cooperate with an emulsion tube in the main air and fuel passage to deliver an efficiently vaporized fuel mixture.

Another object is to provide a carburetor having an improved and simplified construction providing an accelerating pump having a delayed fuel feeding action.

Another object is to provide a carburetor having a new, improved and simplified idling fuel supply means.

Another object is to provide a carburetor having a new and improved casing construction whereby manufacture, assembly, inspection and repair are facilitated.

Other objects and advantages will become apparent from the following description, taken in connection with the accompanying drawings, in which—

While the invention is susceptible of embodiment in many different forms, there is shown in the drawings and shall herein be described in detail, a preferred embodiment, together with various modifications thereof, with the understanding that the present disclosure is to be considered as an exemplification of the principles of the invention and is not intended to limit the invention to the embodiment illustrated. The scope of the invention will be pointed out in the appended claims.

In the form chosen for disclosure herein, the invention is embodied in a downdraft carburetor having a body 14 having a tubular portion 15 forming a main passage 16, with a flange 17 on the portion 15 at the lower end of the passage 16 for connection with an intake manifold, and providing a fuel chamber 18 at one side of the passage 16. Preferably the fuel chamber 18 is formed in two sections 18' and 18'', separable along a vertical plane, with the section 18' cast integrally with the tubular portion 15, and with the section 18'' clamped in place against an interposed gasket 19 by means of screws 20.

Adjacent the upper end of the passage 16 a choke valve 21 is mounted on a rock shaft 22 for actuation by a conventional arm 23 on one projecting end of the shaft.

In the passage 16 below the choke valve 21, there is provided a throttle member 25, mounted on a tubular rock shaft 26 which is parallel to the shaft 22 of the choke valve. The location of these shafts is such that the axis of shaft 26 is perpendicular to the plane of separation of the fuel chamber sections 18' and 18'', and one end of this shaft projects through bearing 27 into the upper portion of the fuel chamber 18 as shown in Figure 1. At its other end the shaft 26 projects through a bearing 28 in the tubular portion 15 and carries at its outer extremity a conventional actuating arm 29.

Fuel is supplied to the fuel chamber 18 by a suitable conduit (not shown) which may be connected to a bushing 30 which is threaded through a boss 31 on the removable section 18'' into the interior of the section as shown in Figure 2. The boss 30 is preferably located so that the bushing axis is horizontal and parallel to the plane of separation of the sections 18' and 18'', whereby the carburetor may be fitted for either right or left-hand mounting merely by provision of differently formed sections 18''. Slidable in the bushing 30 is a valve 32 which, by means of a float 33, is governed to maintain the fuel in the chamber 18 at substantially the level indicated by the line 34. Preferably the float is mounted on a lever 33' which is pivoted on a pin 33'' carried by the member 18'' so as to be positioned within and carried by the removable member 18'' and to move in a plane parallel to the plane of separation of the sections 18' and 18''.

In the preferred form of the invention, the fuel discharge means comprises a fuel duct or

port 35 formed in the throttle 25, the port 35 communicating at its inner end with an axially extending passage 36 in the throttle shaft 26. The passage in the throttle shaft extends into the portion of the shaft which projects into the upper end of the fuel chamber 18 as shown in Figure 1. Various means may be provided for supplying fuel from the lower portion of the fuel chamber to the port 35, although preferably such means assumes the form of a fuel feeding member 40 secured to the throttle shaft 26 so as to swing therewith, the member 40 having a passage therethrough connecting at one end with the passage 36 and at the other end with the surface of said member below the fuel level in the chamber 16 as hereinafter more fully described, to form an inlet.

In the form illustrated in Figures 1 to 10, a tubular fuel feeding member 40 is secured to the projecting end of the shaft 26 adjacent to the bearing 27 and extends radially from the shaft down into the fuel chamber 18. A sleeve-like piston 41, slidable within the member 40, has its lower end spanned by a wall 42 through which an axial bore 43 and an intersecting transverse bore 43' adjacent the lower end provide a portion of a fuel inlet passage. The fuel inlet passage also includes a metering port 44 in a bushing 45 within the upper end of the member 40 (Figure 4), an opening 46 in the upper end of the member 40, and a registering port 47 (Figure 1) in the shaft 26 which opens into the passage 36. The piston 41 cooperates with the cylinder formed by the member 40 to form an accelerating pump, the piston being moved upwardly during opening movements of the throttle 25 by means of an arcuate cam member 48 mounted in the lower portion of the fuel chamber section 18'. The piston 41 at its lower end rides on the cam member 48 so that during swinging movement of the throttle 25 and its shaft 26 (in a clockwise direction as shown in Figure 4) the piston is moved upwardly or toward the axis of the shaft 26. In the idle position of the throttle 25 as shown in Figure 4, the piston is projected or withdrawn to the lower portion of the member 40. An expansive coiled spring 49 positioned between a shoulder 50 on the bushing 45 and an apertured washer 51 acts, through the washer 51 and an internal shoulder 52 against which it bears on the piston 41, to move the piston 41 downwardly and maintain the lower end thereof in contact with the cam 48.

In order to prevent return flow of fuel from the accelerating pump cylinder, a disk-type check valve 53 is positioned in the lower portion of the hollow piston 41 so as to be adapted to close the port 43 during upward movement of the piston. This check valve is of sufficiently light weight so as to be normally raised by incoming fuel and held in the position shown in Figure 4. Preferably a metering pin 54 is carried by the washer 51, the metering pin having a reduced stem 55 secured to the washer and being provided with a larger diameter portion 56 at its upper end which merges with the reduced portion 55 through a tapered portion 57. The larger portion 56 normally lies in and restricts the area of the metering port 44, and it will be readily apparent that when the throttle 25 is moved to its wide-open or full-power position the tapered portion 57 of the metering pin will first be positioned in the port 44 so as to enlarge the area of the port and pass increased quantities of fuel and finally the reduced portion 55.

55 will be positioned in the port 44 so as to give the maximum effectiveness. The metering pin may assume various forms depending upon the characteristics desired.

5 More efficient proportioning of the fuel mixture in the higher speed ranges is obtained in the present embodiment of the invention through the provision, in cooperation with the metering action of the fuel supply member 40, of a vacuum controlled fuel metering means which is preferably mounted in the shaft 26 and governs the effective area of the passage 36. This means in its preferred form is illustrated in Figures 1 and 10, and comprises a metering port 60 formed in the passage 36 adjacent its junction with the port 35 of the throttle.

20 The metering port 60 is controlled by a relatively small metering pin 61 which extends axially through the port 60 from a piston 62 which is slidably mounted in a cylinder portion 62' within the shaft 26 and beyond the port 35 (see Figure 10). An enlarged head 63 in the left-hand end of the pin 61 lies within and reduces the effective area of port 60 when the piston 62 25 is in its right-hand position, while movement of the piston to the left projects the head 63 a substantial distance beyond the port 60 and increases its effective area. The piston 62 moves between limits fixed on the left by a shoulder 30 64 and on the right by a sleeve 65 threaded into the shaft, and an expansive coil spring 66 extending through the sleeve 65 and acting between an end plug 67 in the shaft 26 and the piston 62. 35 The piston 62 serves to urge the metering pin 61 to the left so as normally to provide the maximum effective area for the metering port 60. If desired, a guide pin 68 may extend from the plug 67 through the spring 66. To obtain vacuum controlled actuation of the piston 62, a passage 40 69 formed in the throttle 25 and the shaft 26, and extending in the same direction as the port 35, is connected through an annular groove 70 and a port 71 to the right-hand end of cylinder 62'. When the piston 62 is in its right-hand position of Fig. 10, an annular groove 62'' therein registers with a vent passage 72 to the low suction side of the throttle 25 so as to prevent flow of fuel past the piston. Thus the normal fuel mixture is proportioned efficiently throughout 45 the range of speeds by the cooperative action of the metering pins 54 and 61 which are controlled respectively by the throttle position and the vacuum conditions in the motor.

50 Since there is always a passage of fluid through the port 35, the effect of the suction in the passage 16 will be lower on the left side than on the right side of the piston 62 for the reason that the right side is a dead end. A differential pressure is thus set up which accounts for the 55 resulting movement of the piston 62.

55 For purposes of sudden acceleration, the pumping action of the fuel supply member 40 acts, of course, to force fuel rapidly through the metering port 44, which is opened to its greatest extent by the advancing of its metering pin 54, and this additional fuel passes freely through the metering port 60 under such conditions, since the metering pin 61 will be shifted to the left (Figure 10) due to the drop in vacuum as 60 the throttle is suddenly opened.

65 Preferably, the present invention provides means for augmenting this accelerating charge of fuel through supplying further fuel at such a point in the main passage 16 as to insure 70 thorough and efficient mixture of all of the fuel

75 with the air passing through passage 16. This cooperating fuel supply means is best illustrated in Figures 1, 5 and 9, and comprises a pump 72 arranged for actuation by the shaft 26 of the throttle 25. In the form shown the pump 72 has a cylinder 73 formed integrally within the section 18' radially with respect to the shaft 26 and having a piston 74 therein adapted for action by a cam 75 fixed to the shaft 27 intermediate the fuel supply member 40 and the bearing 21. At its lower end, on the outside of the section 18', the cylinder is closed by a threaded plug 76, and above this plug fuel is admitted to a threaded portion 77 of the bore which forms the cylinder through an inlet port 78. Above 100 the port 78 in the portion 77 of the bore is threaded a plug 79 having an axial passage 80 therethrough opening into the space immediately below the piston 74. In the passage 80 is located a ball check 81 held against undue upward displacement from its seat 82 by a spider-like washer 83. A spring 84 between the washer 83 and the piston 74 normally projects the piston 74, and also serves to hold the washer 83 in position. 105

20 When the piston 74 is depressed by actuation of the throttle 25, the fuel trapped in the cylinder by the check valve 81 is forced upwardly through a passage 85 (Figs. 5 and 9) into a chamber 86 (Fig. 9), through an orifice or jet 87 and thence 30 out of a discharge nozzle or jet 88 into the passage 16. Preferably such discharge is somewhat transversely of the passage just below the level of the throttle 25.

35 After the contents of the pump 72 is discharged, further flow of fuel past the check valve 81 is preferably prevented while the wide-open throttle position is maintained. This end is attained by a spring plunger 90 slidably mounted axially in the piston 74 and projecting downwardly 40 therefrom so that in the discharge stroke of the piston the end of the plunger 90 passes through the spider-like washer 83 to press the ball check member 81 to its seated position. A spring 91, surrounding the plunger within an enlarged bore 45 92 in the piston 74, acts against a flange 93 on the plunger 90 to urge the plunger to its projected position as limited by abutment of the flange with a bearing washer 94 which surrounds the plunger and is fixed in closing relation to the 50 lower end of the bore 92. A reduced continuation 95 of the bore 92 guides the upper end of the plunger 90.

55 The fuel for idling purposes is in the present embodiment supplied by means which includes the fuel passages through the accelerating pump 72 to the discharge nozzle 88. An adjustable primary air supply to the nozzle 88 is provided for idling purposes by a horizontal bore 96 extending 60 through the member 15 into the passage 16 above the level of the throttle 25, with a vertical bore 97 connecting the bore 96 into the passage between the jet 87 and the nozzle 88 (Fig. 9). An adjusting screw 98 threaded into the bore 96, and held in adjusted position by a spring 99, 65 cooperates with the inner surfaces of the bores 96 and 97 to vary the effective area of the passages. By removal of a plug 100 in the chamber 86, the jet 87 may be changed to vary the size of orifice, and thus by means of the jet 87 and 70 the adjustment of screw 98, both the quantity of fuel and quality of fuel mixture may be adjusted.

75 The present invention as embodied in the form illustrated in Figures 1 to 10 preferably provides means whereby an increased idling speed is ob-

tained during use of the choke valve 21. Thus, as shown in Figures 1, 6, 7 and 8, a vertically shiftable stop member 101 is mounted in such a position that the idling position of the throttle 25 may be governed by a plurality of stop shoulders 102, 103 and 104 formed on the stop member. In the form shown the stop member 101 has a lower yoke 105 slidably embracing shaft 26 between the bearing 28 and the arm 29, and a parallel upper yoke 106 slidably embracing the shaft 22 between its bearing and a retaining washer 107 at the end thereof. Formed as a continuation of the throttle arm 29 is an arm 108 carrying an adjustable stop screw 109 adapted for selective engagement with the stop shoulders in accordance with the vertical setting of the stop member 101.

When the choke 21 is closed, a radial arm 110 fixed thereto engages a lug 111 on the yoke 106, so as to raise the stop member toward its upper position of Figure 8, with the result that stop shoulder 104 is effective and a fast idling speed is obtained. When the choke 21 is opened the stop member 101 drops to its lower position so that stop shoulder 102 is effective and the normal idling speed results. In the use of this device, the throttle 25 should be opened as is done by most drivers in starting, thereby facilitating the elevation of the stop member 101. This cooperative action of the choke and the throttle is of particular advantage where an automatic choke is employed, although its usefulness is not limited to such constructions.

The relative position of the working parts may be seen in the diagrammatic view of the device shown in Fig. 14. The tubular portion is shown on the right forming the main passage 16 and on the left is the casing 18' which encloses the fuel chamber 18. Located in the passage 16 is the throttle 25 secured to the throttle shaft 26 with which it rotates. The shaft 26 extends into the fuel chamber 18 wherein the fuel feeding member 40 is attached to it. When the shaft is rotated by means of the actuating arm 29, the throttle 25 is moved between "off" and "on" positions and at the same time the fuel feeding member 40 is swung from one position to another within the fuel chamber 18. Integrally attached to the casing of the fuel chamber 18 is the pump 72, the outside of which is formed by the cylinder 73.

Fluid enters the fuel chamber past the valve shown dotted at 32, and fills the chamber to a level 34 where it is maintained by a float mechanism, omitted from the diagrammatic view of Fig. 14 for the sake of clearness, but which is shown in detail in Fig. 2. Fuel from the chamber passes normally through the axial bore 43 of the fuel feeding member 40, thence upward through the opening 46 into the passage 36 which lies centrally of the shaft 26. Fuel is then conducted through the metering port 60 and thence outward and downward through the port 35 of the throttle into the passage 16.

When the throttle is closed, fuel for idling purposes is drawn from the fuel chamber 18 through the port 78, past the check valve 81 and thence upward through passage 85, from which it is drawn downward and outward from the discharge nozzle or jet 88 into the passage 16. A quantity of air which is drawn through the bores 96 and 97 around the closed throttle unites with the quantity of fuel drawn through the jet 87 into the passage 16 to form a combustible mixture for idling purposes.

When the throttle 25 is opened a sufficient amount, an additional charge of fuel is sent into the passage 16 by means of the pump 72. To produce this added charge, the cam 75 fixed to the shaft 26 drives the piston 14 downward by which action any quantity of fuel trapped below it within the cylinder 73 is forced upward and outward through the passage 85 and nozzle 88 into the air passage 16.

In the embodiment illustrated in Figure 11 of the drawings, the invention is embodied in a carburetor constructed generally along the lines of the embodiment of Figures 1 to 10, but with the fuel feeding member 40 serving as the sole means for providing a rapid feed for accelerating purposes. In this form, the piston and cylinder of the member 40 are made of a greater diameter so as to increase the capacity thereof, and an emulsion tube 115 is suspended axially within the passage 16 beneath the throttle 25. This mounting of the emulsion tube 115 is made by a screw 116 which extends through the wall of the passage 16 and is threaded into a spacing and supporting lug 117 secured to the tube 115. By the use of the emulsion tube 115 suspended relatively close to the outlet port 35 of the throttle, the relatively large quantity of fuel fed through the port 35 is properly directed and mixed with the air as it passes through the carbureting passage.

With the form of accelerating pump or fuel feeding member 40 employed in either of the embodiments disclosed, a prolonged feeding action by the pump may be obtained through the provision of a resiliently mounted cam 48' as shown in Figure 12. In this form, the cam 48' is pivoted on a screw 120 at the end which is engaged by the piston 41 in the closed position of the throttle. At its other end, the cam is guided for pivotal movement by a slot 121 through which a screw 122 extends, and beneath this end of the cam an expansive coiled spring 123 is positioned about a depending lug 124. Upon quick opening of the throttle 25, the cam 48' is depressed so as to compress the spring 123, and by making the spring 123 slightly stronger than the spring 49 of the pump, the cam 48' is gradually elevated so as to cause a prolonged discharge from the pump.

To provide an idling supply of fuel, the embodiment of Figure 11 preferably utilizes the main fuel supply passages from the member 40, and to this end, as shown in Figure 13, an idling fuel discharge orifice 126 is formed in the throttle 25' from the bore of the port 35 downwardly through the side of the throttle which faces downwardly in the closed throttle position. Preferably the orifice 126 is located adjacent to the discharge end of the bore. With the form shown in Fig. 13, an adjustable passage for air 60 is preferably formed about the edge of the throttle adjacent to the port 35, for the purpose of regulating the richness of the idling mixture. Thus a threaded bore 127' is formed in the wall 13 so that the upper and lower edges of the bore 65 are located above and below the throttle faces, and by means of a screw 127 threaded through the bore 127' an adjustable by-pass is formed to vary the amount of air drawn past said edge of the throttle when in idling position. Some fuel 70 is drawn from the port 35 past the edge of the throttle. To effect an adjustment of the idling mixture, the screw 127 is screwed outwardly to permit the throttle valve to shut tighter thereby to reduce the open space at the edge cutting down 75

the passage of air in order to produce a richer mixture. The screw 127 is screwed inwardly to prevent the throttle valve from shutting tightly thereby increasing the opening for air to produce a leaner idling mixture.

In the various forms illustrated herein, the fuel feeding member 49 is provided with an irregular opening 130 through which the reduced and flattened end 131 of the throttle shaft extends. A cap nut 132 is threaded onto the end of the shaft 26 so as to clamp the fuel feeding member against a shoulder on the shaft formed by the reduced portion 131. Thus rotary movement of the fuel feeding member with the shaft is insured. Preferably, as illustrated in Figures 1 and 11, a groove 133 is formed in the shaft intermediate the ends of the bearing 27, and a vent 134 (Figure 5), or a vent 135 (Figure 11), is provided in the body member so as to prevent any syphoning of fuel through the bearing should leakage occur. Additional vent means is also provided for the fuel chamber 18, and such means may take the form of a bored passage 136 (Figure 11) between the interior of the casing section 18' and the upper end of the passage 16, or it may be formed by an upstanding sleeve 137 extending through and riveted to the top of the removable section 18''. On the top of the sleeve 137 is secured a depending skirt 138 which shields the vent openings 30 formed by a transverse bore 139 in the sleeve 137 (Fig. 1).

It is believed readily apparent that the invention provides an extremely simple carburetor having a relatively small number of parts. By 35 providing a fuel discharge orifice which moves downwardly in the body passage as the throttle is opened, the fuel head on the orifice may be varied, and if desired the orifice may be moved from a position above the normal fuel level in the fuel chamber to a position below the normal fuel level. By locating the discharge orifice in the throttle a simple construction is obtained, and as the throttle is opened the fuel discharge orifice moves downwardly with the incoming air 40 so as to provide a prompt response to the demand for fuel. By securing the fuel feeding member to the throttle shaft so that it swings therewith, there are no movable joints in the entire fuel supply passage where detrimental leakage could occur. Furthermore, the fuel supply passage is 45 effectively protected from the heat of the engine, the portion in the throttle shaft and throttle being cooled by the incoming air, and the portion within the fuel chamber by the fuel.

It will also be evident that the invention provides for efficient acceleration through the co-operative action of the two accelerating pumps so as to introduce two separate supplies of fuel into the main carbureting passage. Since one 55 of these accelerating pumps utilizes a portion of the idling fuel supply means, the construction is simplified and the normal fuel supply passage may be more accurately proportioned to handle the normal fuel feed.

The fuel supply means provided is obviously such as to give efficient and economical performance, and in every embodiment is particularly adapted for economical manufacture.

It is believed to be apparent that the form and construction of the fuel supply chamber provided 70 by the present invention is such as to simplify

and reduce the cost of manufacture of the carburetor as a whole, and in addition, it facilitates the inspection of the various operating parts of the fuel supply means. The present form of casing provides for the fixed mounting of the one pump 72, as well as for the positioning of the member 68 within a rigid portion of the chamber 18 so as to be housed and protected thereby while being readily accessible for inspection or repair. In addition, the float and the supply 10 connection are associated with the removable section so as to facilitate such inspection of the other parts, and in such mounting the float is fully housed and protected.

By reason of the relatively large area capacity 15 of the passage 36, and the location of the metering port 60 relatively close to the discharge orifice 35, the opening of the port 60 by operation of its vacuum controlled metering pin results in an instantaneous increase in the fuel feed, where- 20 by to render the motor more responsive.

I claim as my invention:

1. A carburetor comprising, in combination, a body member having a main passage and a fuel chamber, a throttle in said main passage having 25 a fuel passage therein terminating in a discharge orifice, means for supplying fuel from said chamber to said main passage, said means comprising a pair of accelerating pumps supplied from said chamber and operated to discharge fuel in response to the opening of said throttle, one of said pumps being connected to discharge through said orifice, and the other of said pumps being connected to discharge at another point in said main 30 passage. 35

2. A carburetor comprising, in combination, a body providing a main passage and a fuel chamber, a throttle in said passage having a fuel passage formed therein terminating in a discharge port adjacent to one edge of said throttle, 40 a shaft supporting said throttle and having one end projecting into said chamber, said end having an axial bore therein connecting with said fuel passage, a fuel feeding member projecting substantially radially from said end of said shaft and arranged for swinging movement therewith, said member being arranged for feeding of fuel to said bore, a separate idling fuel supply means fed from said chamber, an accelerating pump in said chamber, arranged to discharge through said idling fuel supply means, and a cam on said end of said shaft for operating said pump. 45 50

3. A carburetor comprising, in combination, a body having a main passage and a fuel chamber at one side thereof, a throttle in said passage having a fuel passage therein terminating in a discharge orifice, a rock shaft supporting said throttle and having an axial bore forming a continuation of said fuel passage toward one end of said shaft, said end of the shaft projecting into said chamber, an accelerating pump mounted on said end of the shaft to discharge into said bore and to swing with said shaft, means to operate said pump as it swings in the opening movement of said throttle, a second accelerating pump mounted in a fixed position in said chamber, said second pump being arranged to discharge into said main passage, and a cam on said shaft for operating said second pump. 55 60 65
